UNITED STATES PATENT OFFICE.

JAMES J. WALSH, OF PARIS, TEXAS.

SUPPORT FOR ELECTRIC LIGHTS.

SPECIFICATION forming part of Letters Patent No. 471,837, dated March 29, 1892.

Application filed September 15, 1891. Serial No. 405,790. (No model.)

To all whom it may concern:

Be it known that I, JAMES J. WALSH, a citizen of the United States, residing in Paris, county of Lamar, and State of Texas, have invented certain new and useful Improvements in Supports for Electric Lights, of which the following is a specification.

This invention relates to supporting devices for electric-arc lamps, the object being 10 to provide a device which will automatically release itself when the lamp is to be lowered and which when the lamp is raised to the point of suspension will automatically catch and hold the lamp in suspended position.

15 The invention consists in the combination, with the lamp, of a **V** or **U** shaped pivoted lever, one arm of the lever being bent inward to form a hook and being weighted to act in conjunction with an eccentrically - located 20 pivot to catch and release the lamp.

The details of the invention will be described with reference to the accompanying drawings, in which—

Figure 1 is a perspective view of the lamp 25 and its supporting device, and Fig. 2 is a side elevation of the upper portion of the lamp with the suspending device.

A represents the lamp; B, the lamp-hood, and C a cross-piece arranged at the top of the 30 lamp and carrying at its extremities insulators c c, which support the wires c' c', which supply current to the lamp. These wires lead off to a neighboring pole or other support and serve to prevent the lamp from turning 35 or twisting on the vertical axis.

D represents a cable, mast-head, or other suitable support for the lamp. Near the point where the lamp is to be suspended a pulley e is located and supported by the cable D.

40 Over this pulley a cord or rope f passes and connects at one end with the cross-piece C of the lamp - frame. Thence it leads over the pulley, and thence over suitable guides to a point where it is convenient for manipulation.

45 On the upper side of the cross-piece C and near its middle point a post g is fixed, the upper end of which is bifurcated and receives the bearings of a pivot-pin g'.

G is an angular lever formed by two arms 50 connected together at one end, diverging from

the point of connection and forming a figure similar to the letter **V** or the letter **U**. This lever is pivoted upon the pin g' at a point slightly to one side of the apex of the arms, and the arm g², which is farthest from the 55 pivot, is weighted and formed at its upper end into a hook g³, bent inward toward the other arm.

g⁴ represents a stop for supporting the lever on one side, and the position of the lever 60 when the lamp is not suspended is, as shown in Fig. 2, against the stop.

The operation of the device is as follows: Assume the lamp to be lowered and the arm G in the position shown in Fig. 2. The lamp 65 is lifted by pulling on the cord f, and while ascending the lamp is prevented from twisting by the two wires c' c'. It is lifted until the arm g⁵ of the lever G strikes the cable D. The upward movement then being continued, 70 the arm g⁵ is forced downward, thus throwing the arm g² over against the cable D, (the cable striking the arm g² at about the point indicated by dotted lines D'), where it remains owing to the fact that its center of gravity 75 has passed the pivotal center. The lamp is then lowered, and the hook g³ catches upon the cable and suspends the lamp. While the hook is lowering onto the cable the arm g² is being thrown slightly back again across the 80 pivotal center, so that when the lamp is suspended the center of gravity of the lever is on the left side of the pivot. To release the lamp and lower it, the cord is again pulled and the lamp lifted until the point of the hook 85 is clear of the cable. When it is thus free, the arm falls to the left against the stop g⁴, thus releasing the lamp and allowing it to be lowered.

It will be observed that the principal feature 90 of this catch and release device is its simplicity and the fact that it is not liable to get out of order. The exact shape and angle of the arms of the lever G may be altered to some extent without departing from the spirit 95 of the invention.

I claim as my invention—

The combination, with an arc lamp or other device to be suspended, of a cord attached to the same for raising and lowering, a support 100

for said lamp, such as a cable or mast-arm, and a V-shaped lever pivoted eccentrically to the lamp or device, one arm of the lever having a hook adapted to engage with said cable or mast-arm and the other arm of the lever being arranged to strike the cable or mast-arm and throw the hook into engagement therewith.

In witness whereof I have hereunto affixed my name in the presence of two subscribing witnesses.

JAMES J. WALSH.
